US00D933287S

(12) **United States Design Patent** (10) **Patent No.:** **US D933,287 S**
(45) **Date of Patent:** **** Oct. 12, 2021**

(54) **VAPORIZER DEVICE DOCK**

(71) Applicant: **JUUL Labs, Inc.**, San Francisco, CA (US)

(72) Inventors: **Brandon Cheung**, San Francisco, CA (US); **Andrew L. Murphy**, San Francisco, CA (US); **John Travis Wettroth**, San Francisco, CA (US); **Ryan M. Wolff**, San Francisco, CA (US); **Jeffrey M. Quackenbush**, San Francisco, CA (US)

(73) Assignee: **JUUL Labs, Inc.**, San Francisco, CA (US)

(**) Term: **15 Years**

(21) Appl. No.: **29/730,160**

(22) Filed: **Apr. 1, 2020**

(51) **LOC (13) Cl.** **27-02**

(52) **U.S. Cl.**

(57) **CLAIM**

The ornamental design for a vaporizer device dock, as shown and described.

DESCRIPTION

FIG. 1 is a bottom, front, and left side perspective view of a vaporizer device dock showing our new design;

FIG. 2 is a top, front, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 6 Drawing Sheets
